UNITED STATES PATENT OFFICE.

LOUISE S. KRACKE, OF CHICAGO, ILLINOIS.

WINDOW-CLEANER.

1,378,243.

Specification of Letters Patent. Patented May 17, 1921.

Application filed November 16, 1920. Serial No. 424,494.

To all whom it may concern:

Be it known that I, LOUISE S. KRACKE, a citizen of the United States, and a resident of Chicago, in the county of Cook and State 5 of Illinois, have invented certain new and useful Improvements in Window-Cleaners, of which the following is a specification.

This invention relates to improvements in devices to be used for cleaning the glass

10 panes of windows, and it consists in certain peculiarities of the construction, novel arrangement and operation of the various parts thereof, as will be hereinafter more fully set forth and specifically claimed.

15 The principal object of the invention is to provide a cleaner for windows which shall be so made as to be particularly adapted for cleaning the panes of both the upper and lower sashes of windows without the necessity of the operator getting outside of the

20 sashes or window frame.

Another object of the invention is to provide a cleaner or polisher for windows or other flat surfaces, such as walls and ceilings of rooms, the tops of tables, and the walls of furniture, which can be operated manually or when necessary, by means of a detachable handle.

Still another object of the invention is to 30 provide simple and efficient means for easily securing over the rubbing face of the body of the cleaner a piece of cloth or similar material in such a manner that it can be readily detached therefrom for the purpose of being washed or renewed.

A still further and important object is to furnish a cleaner of such shape, compactness or dimensions, especially in thickness, as to permit of its insertion and effective operation between and on the adjacent surfaces of the window panes when they are placed in parallelism by raising the lower sash or lowering the upper sash in the operation of cleaning the windows.

45 A further object is to provide a cleaner for windows and the like of the above mentioned general character, which shall be simple and inexpensive in construction, strong, durable and efficient in operation.

50 Other objects and advantages of the invention will be disclosed in the following description and explanation.

In the accompanying drawing which

serves to illustrate an embodiment of the invention—

55

Figure 1 is a rear face view of the cleaner showing the parts in their normal positions and illustrating the handle shortened for the convenience of illustration.

Fig. 2 is a longitudinal sectional view 60 taken on line 2—2 of Fig. 1 looking in the direction indicated by the arrows.

Fig. 3 is a front or face view of the cleaner showing a fragment of a cleaning cloth in about the position it may be held thereon 65 near its ends when such cloth is used in connection with the cleaner, and

Fig. 4 is an edge view of the body of the cleaner and a portion of the handle thereof.

Like numerals of reference refer to corresponding parts throughout the different views of the drawing.

The reference numeral 5 designates the body of the cleaner, which may be made of any suitable size, form and material, but 75 preferably, substantially triangular in shape as shown and of metal. This body is provided on one of its surfaces, which will hereinafter be called the rubbing or front surface, with a depression 6 which is substantially coextensive with the body 5 and of the same shape and is formed by means of forwardly extended flanges 7 provided on each of the edges of the body.

Within the depression 6 is located a pad 85 or plate 8 of resilient material such as rubber, which is transversely corrugated or formed with transversely extended ribs 9 as is clearly shown in Fig. 2 of the drawing. The free edges of the ribs 9 of the member 8 90 project forwardly of the flanges 7 so as to be adapted for contact with the panes of glass or other flat surface. By this arrangement it is apparent that the resilient ribs which are spaced from one another will act to thoroughly remove water from the glass panes when the device is moved back and forth over the surface thereof and thus will effectually clean the panes.

By reference to Fig. 2 of the drawing, it 100 will be seen that the upper portion of the body or plate 5 or that part thereof opposite the base of the triangular figure is thickened and is provided with a groove or notch 10 on its outer surface and that the opposite 105 portion of the body 5 or the base of the

triangular figure formed by said body is provided with a pair of alined but spaced enlargements 11, see Figs. 1 and 2, each of which has in its outer end an opening to receive the ends 12 of a wire clamp 13 which is triangular in shape as shown, or of a shape to correspond with the shape of the body 5 and of a size to fit snugly but detachably around the perimeter of said body.

10 The plate or body 5 is provided on its rear surface about midway between the base of the triangular figure or body 5 and its opposed apex with a pair of spaced bosses 14 each of which is provided in its inner end with an opening 15 for the reception of outward or lateral extensions 16 on a pair of slightly resilient arms 17 which constitute a part of the handle of the cleaner.

As shown in Figs. 1 and 2 of the drawing, 20 the arms 17 are bowed or curved from each other beginning at the juncture thereof with the extensions 16 and terminating at a point near the base of the triangular body or plate from which latter point they are located in 25 parallelism with one another and by preference are held together side by side by means of a clip 18 surrounding the same and soldered or otherwise fastened thereto. By reference to said views of the drawing it 30 will be further seen that the arms 17 are curved outwardly from the plate or body 5 for a slight distance and are then extended in a straight line. By this construction, it is obvious that when the extensions 16 of the 35 arms 17 are inserted in the openings 15 of the bosses 14, the plate or body 5 will be carried by said arms in such a way that said body will have tilting movement on the extensions 16 thus enabling the rubbing surface or front of the body to be maintained 40 in proper position on the pane of glass or other surface being cleaned no matter what position the handle of the device may occupy.

45 Furthermore, it is evident that pressure on the arms 17 will, by reason of the peculiar formation of said arms, have a tendency to force the extensions 16 outwardly and thus prevent their accidental dislocation or dis- 50 placement from the openings 15 for said ex- tensions in the bosses 14 of the body. The outer or free ends of the arms 17 are fastened in any suitable manner to one end of a section 19 of the handle, the other end of 55 which is provided with a socket 20 to receive a detachable section 21 of the handle, which latter section may be used when desired. The wire clamp 13 is by preference covered at its sides and base portions with rubber 60 tubing 22 which will assist the clamp 13 in holding in position on the body 5 a cleaning cloth 23 or a piece of any other suitable cleaning material which may be interposed between the body 5 and the clamp 13 by dis- 65 engaging the apex or portion of the clamp

opposite the base of the body or triangular figure from the retaining groove 10 in the apex of said body opposite its base when it is apparent that the clamp may be turned on its pivots formed by the ends 12 of the clamp 70 13 and the bearing enlargements 11 of the body of the cleaner. When thus separated the ends of the cleaning cloth 23 may be placed across the plate or body 5 on the front or rubbing surface thereof in about 75 the position shown in Fig. 3 of the drawing, when by pressing the clamp 13 into engagement with the body 5, it is manifest that the cloth will be held against accidental dislocation in such a way that it can be used for 80 wiping or washing the surface to be cleaned.

By my improvements, it will be understood that the jointed or sectional handle will provide means for reaching to the top of the window pane or panes of the upper 85 sash while the latter is in its normal position, and thus enable the entire surface of the panes of said sash to be thoroughly cleaned on the inside of the room.

Assuming that the lower sash is in its normal position, the upper sash can be lowered to any desired distance, thus separating the meeting rails of the sashes and permitting the cleaner to be inserted therebetween and used for cleaning the adjacent surface of the 90 sashes. By further lowering the upper sash, it is manifest that the outer surface of the panes thereof may be cleaned by reaching over the top of the thus lowered upper sash and applying the cleaner to the outer surface of its panes without the necessity of getting outside of the window frame.

Having thus fully described my invention, what I claim as new and desire to secure by Letters Patent is:

1. In a window cleaner, the combination with a thin flat substantially triangular shaped body having its faces parallel and provided on one of its faces with a depression substantially co-extensive with said face, said body having at one of its ends a pair of spaced apart alined enlargements, each of said enlargements having in its outer end an opening, of a clamping member corresponding in shape to that of said body 110 adapted to fit around the perimeter of the latter, said clamping member having its adjacent ends located in the openings of said enlargements for pivotally connecting the clamping member and body together, and a 115 transversely ribbed pad located in the said depression of the body.

2. In a window cleaner, the combination with a thin flat substantially triangular shaped body having its faces parallel and provided on one of its faces with a pair of spaced bosses, each of said bosses having in its inner end an opening, said body having at one of its ends a pair of spaced apart alined enlargements, each of said enlarge- 120 125 130

ments having in its outer end an opening, of a clamping member corresponding in shape to that of said body adapted to fit around the perimeter of the latter, said 5 clamping member having its adjacent ends located in the openings of said enlargements for pivotally connecting the clamping member and body together, and a handle for the body including a pair of resilient arms pro-

vided at one of their ends with lateral extensions located in the openings of said bosses, said arms being oppositely curved from one another and also curved upwardly from the body and longitudinally with respect thereto, the outer portions of said arms 115 being located in parallelism and connected together.

LOUISE S. KRACKE.
